(57) **CLAIM**

The ornamental design for a swimming pool cleaning robot, as shown and described.

DESCRIPTION

FIG. 1 is a first perspective view of a swimming pool cleaning robot, according to the first embodiment, showing the new design.

FIG. 2 is a second perspective view thereof.

FIG. 3 is a third perspective view thereof.

FIG. 4 is a fourth perspective view thereof.

FIG. 5 is a front view thereof.

FIG. 6 is a rear view thereof.

FIG. 7 is a left-side view thereof.

FIG. 8 is a right-side view thereof.

FIG. 9 is a top view thereof.

FIG. 10 is a bottom view thereof.

FIG. 11 is a first perspective view of the swimming pool cleaning robot, according to the second embodiment.

FIG. 12 is a second perspective view thereof.

FIG. 13 is a front view thereof.

FIG. 14 is a rear view thereof.

FIG. 15 is a left-side view thereof.

FIG. 16 is a right-side view thereof.

FIG. 17 is a top view thereof.

FIG. 18 is a bottom view thereof.

FIG. 19 is a first perspective view of the swimming pool cleaning robot, according to the third embodiment.

FIG. 20 is a second perspective view thereof.

FIG. 21 is a front view thereof.

FIG. 22 is a rear view thereof.

FIG. 23 is a left-side view thereof.

FIG. 24 is a right-side view thereof.

(Continued)

FIG. 25 is a top view thereof; and,
FIG. 26 is a bottom view thereof.

The disclosure for the second embodiment has two bottom wheels and the disclosure for the third embodiment has four bottom wheels.

The broken lines shown in the drawings are for the purpose of illustrating portions of the swimming pool cleaning robot that form no part of the claimed design.

1 Claim, 20 Drawing Sheets
